INVENTOR

John A. Henderson

BY Richard Oliver.

ATTORNEY

UNITED STATES PATENT OFFICE.

JOHN A. HENDERSON, OF PORTLAND, OREGON.

WEATHER-STRIP.

1,317,974.

Specification of Letters Patent.

Patented Oct. 7, 1919.

Application filed August 10, 1917. Serial No. 185,598.

To all whom it may concern:

Be it known that I, JOHN A. HENDERSON, a born citizen of the United States, residing at Portland, in the county of Multnomah and 5 State of Oregon, have invented certain new and useful Improvements in Weather-Strips, of which the following is a specification.

This invention relates to new and useful 10 improvements in weather strips for doors and windows and the principal object of the invention is to provide a device of this nature, more particularly adapted for use on casement windows, which will permit the 15 sash to be hung to swing inwardly, instead of outwardly.

Another object of the invention is to provide a device of this character which will work by gravity and without the use of 20 springs or the like.

A further object of the invention is to provide a device which will completely close the space between the bottom of the sash and the frame so as to prevent the entrance of 25 wind, rain or snow while permitting free movement of the sash when being opened or closed.

In carrying out my invention I utilize a metal strip pivoted in a recess formed in the 30 bottom edge of the sash and carrying a piece of felt at one edge and a counterbalancing weight at its other edge for normally holding the strip within the recess. I provide a pivoted member adapted to engage a part 35 of the window frame when the sash is closed so as to be forced inwardly against the strip to swing the same downwardly into position to cause the felt to be pressed against the sill.

40 Another object of the invention is to provide a device of this character, which is simple and durable in construction, reliable and efficient in operation and one which can be manufactured and placed upon the 45 market at a minimum cost.

The invention also consists in certain other features of construction and in the combination and arrangement of the several parts, to be hereinafter fully described, 50 illustrated in the accompanying drawings and specifically pointed out in the appended claim.

In describing my invention in detail, reference will be had to the accompanying 55 drawings, wherein like characters denote

like or corresponding parts throughout the several views, and in which:—

Figure 1 is an edge view showing the lower part of the sash with my invention applied thereto.

60

Fig. 2 shows one corner of the sash provided with my invention.

65

Fig. 3 is a horizontal transverse section showing part of the sash and the window frame with the parts in closed position.

Fig. 4 is a vertical transverse section with the parts in the position shown in Fig. 3.

Fig. 5 is a view of the weather strip with parts broken away, and

Fig. 6 is a cross section through the 70 weather strip.

In these figures 1 represents part of the window frame, 2 the casing, 3 the sill and 4 the stool. 5 represents the sash which may be pivoted or hinged and adapted to swing 75 inwardly. 6 represents a recess formed in each side of the window frame to receive the sash, as is well known.

In carrying out my invention I provide a recess 7 in the bottom edge of the sash, said recess having a curved inner wall while adjacent the outer edge of the sash the recess is provided with a rectangular portion 8 of reduced depth. 9 represents the weather strip pivoted in the said recess by means of 80 the rod 10. This weather strip is formed of sheet metal folded upon itself and at the folded part being looped around a rod 11 and then having the two portions of the sheet brought together and extended parallel to about midway of the strip where one of the portions is looped around the pivotal rod 10 and then the two portions are brought together again and extend parallel to a point adjacent the free ends, where said ends 85 are curved downwardly and spaced apart so as to grip the piece of felt 12 between them. The weather strip is of sufficient length to extend substantially across the lower edge of the sash but being slightly 90 shorter than the sash so as to fit between the pair of plates 13 located at the bottom of each side edge of the sash, each of said plates having an opening therein to receive the end of the rod 10 to pivot the same in position.

100 The weather strip is so proportioned that it will lie entirely within the recess 7 and its extended portion 8 and the rod 11 will act as a weight to normally hold the weather strip within the recess as clearly shown in Fig. 1. 110

The plate 13 covers the rectangular recess 14 formed in the lower side edge of the sash and this recess communicates with the ends of the recess 7, it being understood that there is a recess 14 on each side edge of the sash. The said recess extends through the outer side of the sash and the plate 15, having a slot 16 in its lower part, is secured to the outer side of the window and covers said recess. A lever 17 is located in the said recess and has its upper end pivoted to the sash in the upper part of said recess, as at 18, and said lever is provided with an enlarged head 19 having its lower end rounded and having an inclined part connecting said rounded end with the main part of the lever. Thus a projecting point 20 is formed at the point where the inclined part joins with the rounded end and this point engages the weather strip, thereby reducing the friction of the lever on the weather strip. The lever is so located that the rounded end of the head thereof will project through the slot 16 in the plate 15 and will contact with the bottom of the recess 6 in the window frame when the sash is closed. To prevent wear of the frame I locate a plate 21 on the bottom of this recess with which the lever will engage. On the outer edge of the stool 4 I provide an inclined part 22 to receive the felt 16 carried by the weather strip.

When the window is opened the weight of the rod 11 will overcome the weight of the lever 17 so that the weather strip and lever will assume the positions shown in Figs. 1 and 2, said lever having a portion projecting through the slot 16 and the weather strip being parallel with the bottom edge of the sash and being within the recess. When the sash is closed the rounded end of the enlarged head of the lever 17 will come in contact with the plate 21 so that the said lever will be forced inwardly and downwardly thus pressing against the weather strip so as to force the outer edge downwardly while the end carrying the rod 11 will swing upwardly within the recess. Thus the felt 12 is pressed against the inclined part 22 of the stool thus closing the space between said stool and the lower edge

of the sash. I locate a strip 23 of rubber or the like in the upper part of the recess 7 with which the inner edge of the weather strip will engage when the same is forced upwardly by the lever. This will prevent the wind from passing through the recess 7 in the sash and thus entering the room.

It will be understood that the lever 17 may be made in a different way from that shown. For instance it may be provided with a screw on its lower end which will come in contact with the plate 21 so that the pressure of the said lever on the weather strip may be regulated.

While I have shown the invention applied to a window it will of course be understood that it may be applied to doors as well, and due to the fact that a considerable space may be left between the bottom edge of the door and the sill, the door will readily pass over rugs and the like.

It is thought from the foregoing that the advantages and novel features of my invention will be readily apparent.

I desire it to be understood that I may make slight changes in the construction and in the combination and arrangement of the several parts, provided that such changes fall within the scope of the appended claim.

I claim:—

The combination with a sash having a recess in its lower edge, of a member pivoted in said recess and normally tilting out of operative position, a lever pivoted in said recess above the pivot of said member and adjacent the inner side of said recess, the lower end of said lever projecting through and beyond the outer face of said sash, said lower end of the lever being semi-circular in configuration to exert a camming action between the outer end of said member and a window frame to tilt and retain the outer end of said member in close engagement with a sill when the sash is closed.

In testimony whereof I affix my signature in presence of two witnesses.

JOHN A. HENDERSON.
